UNITED STATES PATENT OFFICE.

ELMER O. BEARDSLEY AND WALTER F. PIPER, OF CHICAGO, ILLINOIS.

MACHINE FOR MAKING MOLEDS FOR FOUNDRY.

1,351,227.

Specification of Letters Patent. Patented Aug. 31, 1920.

Application filed December 12, 1919. Serial No. 344,378.

To all whom it may concern:

Be it known that we, ELMER O. BEARDSLEY and WALTER F. PIPER, both citizens of the United States, and residents of Chicago, in the county of Cook and State of Illinois, have invented certain new and useful Improvements in Machines for Making Molds for Foundry, of which the following is a full, clear, and exact description.

10 The invention relates to machines for making molds for founding.

One object of the invention is to provide an improved machine in which the flask is movably mounted beneath a sand projector by improved means.

Another object of the invention is to provide an improved machine with a projector which is mounted to rotate in a circular path to facilitate the feeding of the sand from the floor. A still further object of the invention is to provide a rotary machine in which the flask is suspended so that the surplus sand may be scraped from the flask to the front of the sand delivery devices where it will be picked up and again delivered to the machine. Another object of the invention is to provide an improved molding machine in which the projector for throwing sand into the mold is mounted upon a rotatable support. Another object of the invention is to provide an improved machine for making molds in which the support for the flasks is adapted to be moved horizontally relatively to the projector without varying the angle of delivery. Another object of the invention is to provide improved means for feeding sand to the projector. Another object of the invention is to provide improved means for propelling the projector support and sand delivery means. Other objects of the invention will appear from the description.

In the drawings: Figure 1 is an end elevation of a machine embodying the invention. Fig. 2 is a rear elevation. Fig. 3 is a detail section of the sand projector. Fig. 4 is a section taken on line 4-4 of Fig. 5. Fig. 4' is an inverted plan of the flask-support and its connections. Fig. 5 is a plan, parts being omitted. Fig. 6 is a plan of the base of the rotatable carriage. Fig. 7 is a section taken on line 7-7 of Fig. 5. Fig. 8 is a section taken on line 8-8 of Fig. 5.

The machine comprises a carriage which is horizontally rotatable and adapted to sustain the sand-projector and its operating

mechanism, the sand-elevating and feeding mechanism and the conveyer for delivering the sand to the feed mechanism. The base of the carriage comprises a bracket 10, a 60 socket 11 rotatably held upon a fixed trunnion or mast 12 and a back plate 14 fixed to said bracket. The connection between bracket 10 and socket 11 comprises a pin 15 extending transversely through and held in 65 the socket 11 and extending through slots 18 in the arms 17 of the bracket 10. Set screws 19, threaded to the arms, are adapted to engage said pin to adjustably connect the bracket to the socket so that the bracket may 70 be raised or lowered relatively to the floor. A carriage standard 13 is secured to the bracket 10.

A sand projector comprising a rotor 20 and a casing 21 and of the construction set 75 forth in Letters Patent No. 1,309,823 is adapted to project sand into flasks 22a. The casing 21 of this projector is suitably secured to and supported by a bracket 21a which is secured to a tubular arm 22 by 80 U-bolts 23. Arm 22 is rigid and rotatable with the carriage. The inner end of arm 22 is secured in and to standard 13 by a U-bolt 24 and its outer end is secured by U-bolts 25 to a bracket 26a which is secured to the outer 85 end of the back 14 of the carriage.

The shaft 26 for the rotor 20 has its outer end supported in a bearing 27 in bracket 21a and its inner end in a bearing 28 on the carriage standard 13. An electric motor 29 is 90 movable with the carriage and is suspended from a bracket 30 which is fixed to the standard 13. The shaft of said motor is coupled to drive the shaft 26 at high speed necessary to operate the propeller blade 31 on the rotor 20 of the sand-projector. Sand is delivered into one side of the projector by an inclined chute 32, the lower end of which is supported on the projector-casing 21 and the upper end on the carriage-standard 13. 100 A screen 33 is provided in this chute to sift the sand and the material which does not pass through the screen is shunted to one side of said chute by a deflector 34.

A desideratum of the present invention is 105 to provide a movable support for the flask which is adapted to be moved laterally under the projector to fill all portions of the flask without varying the angle of delivery of the sand. This support is carried by the rotatable carriage on which the projector is mounted. A bearing bracket 36 is rigidly

secured to and adjustably clamped on the arm 22 by U-bolts 37. A spindle 38 is mounted in an anti-friction bearing in bracket 36 and a tubular jib 39 is rigidly secured to said spindle by a U-bolt 40. A bearing socket 41 is rigidly secured and clamped to the jib 39 by a U-bolt 42. A spindle 43 is rotatably mounted in socket 41. A tubular arm 44 has its inner end secured 10 to spindle 43 by a U-bolt 45 which passes around the spindle and through said arm. A plate 46, adapted to serve as a support for a flask to be filled with sand from the projector, is mounted on a stud 47 which is rotatably held in a socket 47^a which is secured by a U-bolt 48 to the outer end of arm 44. The axes of the pivotal connections for the jib and arm and plate are vertical so that the plate 46 will remain horizontal and the 15 angle of delivery of the sand from the projector into the flask will not be varied, while the pivotal connections for the jib and arm permit the flask and support 46 to be moved horizontally in any direction so that all portions of the flask may be brought into position to be filled with sand from the projector. This construction exemplifies a machine in which the projector is mounted upon a movable carriage and the latter is 20 provided with a movable flask support which is mounted on the carriage and movable relatively thereto.

The carriage is rotatable so that it may be moved in a circular path over an area 25 of the floor on which the molding sand has been shoveled and to progressively advance over this area as the sand on the floor is fed to the machine. While the machine is rotatably advancing, sand may be placed in back of it so that the machine will be continuously supplied with sand. A screw-conveyer 50 is secured to a shaft 51 which has its outer end mounted in an extension 52 of the back 14 and its inner end in a bearing 30 Fig. 2 is a rear elevation. Fig. 3 is a detail of the back 14 is curved, as at 54, to coöperate with the screw in feeding the sand to an elevator adjacent the inner end of the screw-conveyer. This elevator consists of 35 an endless chain 55 and buckets 56. These buckets are mounted on the spindles 57 which connect the links of the chain and project from one side thereof. The buckets are mounted on the projecting portions of 40 said spindles and disposed at one side of the chain instead of in alinement therewith. By this arrangement, the conveyer-chain is kept free from sand. Chain 55 passes around a sprocket 58 fixed to the screw-conveyer shaft 51, a sprocket 59 which is mounted adjacent one end of a lever 60 and a sprocket 61 adjacent the other end of said lever. The latter is pivoted between the sprockets, as 45 at 62, and is held in position to keep the chain under the desired tension by a cable 50

63 which is connected to one end of the lever 60 and has its other end connected to an adjustable drum 64. A spring 65 is included in the cable 63. Chain 55 also engages and is driven by a sprocket 66. Besides operating the elevator buckets, this chain operates the sprocket 58 on the screw-conveyer shaft. Sprocket 66 is secured to a shaft 67 which is mounted in a bearing 68 on standard 13 and is driven from the motor 70 29 by a pinion 69 on shaft 26 and a gear-wheel 70 on shaft 67 and meshing with said pinion.

Mechanism is provided for rotating the carriage to cause the conveyer-screw to be 80 moved so that it will be progressively shifted toward the sand-pile which may be constantly maintained by shoveling the sand in back of the carriage. This mechanism comprises a gear-wheel 72 which is rotatable 85 around a stud 73 projecting from the end of bracket 52, a circular rack 71 which is formed of sections and bolted to the floor of the molding room and with which gear 72 meshes, and reducing gearing driven 90 from the screw-conveyer shaft 51 to cause the carriage to rotate slowly so that the screw will be kept supplied with sand. This gearing comprises an eccentric or wrist-pin 74 on the outer end of shaft 51, a pawl 75 pivoted on the wrist-pin and pressed by 95 a spring 76 into engagement with a ratchet-wheel 77 which is journaled on the stud 73, a pinion 78 on the hub of ratchet 77, idler pinions 79 journaled on the studs 80 on the bracket 52 and internal gear-teeth 81 on the gear-wheel 72. As the shaft 51 is rotated, the wrist-pin 74 will operate pawl 75 to rotate the ratchet-wheel 77 step-by-step. The gearing between ratchet 77 and 100 gear 72 will cause the wheel 77 to be driven at a reduced speed. Rotation of gear 72, which meshes with the stationary rack, will cause the carriage on which the projector, elevator and feed-mechanism are mounted 105 to be rotated. A dog 83 pivoted to the bracket 52, is provided with a terminal 84 which is adapted to ride in the rack 71 and is yieldingly held in engagement therewith by a spring 85. This dog serves to remove 110 the sand from and clear the rack 71 in advance of the gear 72.

The operation of the machine will be as follows: The flask 22^a to be filled and with the pattern therein is placed on the support or table 46. The screw-conveyer 50 will force the sand toward the inner end thereof and so that it will be picked up by the elevator buckets 56 which will elevate the sand and dump it onto the screen 33 115 through which the sand will fall into the chute 32 and be delivered into one side of the projector. The projector blade 31 will be operated to propel the packed wads of sand at a speed ranging from approximately 120 125 130

4000 to 8000 feet per minute as more fully set forth in the aforesaid Patent No. 1,309,833. The operator will shift the flask support and flask laterally relatively to the projector, the arm and jib-connection permitting such movement until all portions of the flask have been properly filled. When that has been done, the operator usually strikes off the flask and by throwing the sand toward the front of the conveyer it will fall where it will be again picked up by the conveyer. It will be understood that the floor is usually covered with a pile of sand and as the machine rotates the pile in the back of the conveyer may be refilled so that the machine may be continuously supplied with sand without having a long runway traversed by the machine.

The invention exemplifies an improved molding machine adapted to project sand into flasks and in which the projector, flask, support, sand-conveying and elevating mechanism are mounted on a movable or rotatable carriage. Also one in which provision is made for gradually rotating the carriage to keep the machine supplied with sand from a circular pile which can be constantly kept up to keep the machine in continuous operation. Also a machine in which the flask support and the sand projector are both movable together and are movable relatively to one another.

The invention is not to be understood as restricted to the details set forth, since these may be modified within the scope of the appended claims, without departing from the spirit and scope of the invention.

Having thus described the invention, what we claim as new and desire to secure by Letters Patent, is:

1. In a molding machine, the combination of a movable carriage, a sand projector comprising a stator and a rotor mounted on the carriage, a flask-support mounted on the carriage, means mounted on the carriage for feeding sand to the projector and means to permit relative lateral movement between the projector and the flask-support to fill all portions of the flask.
2. In a molding machine, the combination of a movable carriage, a sand projector comprising a stator and a rotor mounted on the carriage, a motor for driving the rotor mounted on the carriage, a flask-support mounted on the carriage, means mounted on the carriage for feeding sand to the projector, and means to permit relative lateral movement between the projector and the flask-support to fill all portions of the flask.
3. In a molding machine, the combination of a rotatable carriage, a sand projector comprising a stator and a rotor mounted on the carriage, a flask support mounted on the carriage, means mounted on the carriage for

feeding sand to the projector, and means to permit relative lateral movement between the projector and the flask-support to fill all portions of the flask.

4. In a molding machine, the combination of a rotatable carriage, a sand projector comprising a stator and a rotor mounted on the carriage, a motor for driving the projector, mounted on the carriage, a flask support mounted on the carriage, means mounted on the carriage for feeding sand to the projector, and means to permit relative lateral movement between the projector and the flask-support to fill all portions of the flask.

5. In a molding machine, the combination of a movable carriage, a sand projector comprising a stator and a rotor mounted on the carriage, a flask-support mounted on the carriage, means mounted on the carriage for feeding sand to the projector, and means to permit relative lateral movement of the flask-support relatively to the projector to fill all portions of the flask.

6. In a molding machine, the combination of a movable carriage, a sand projector comprising a stator and a rotor mounted on the carriage, a motor mounted on the carriage for driving the projector, a flask support mounted on the carriage, means mounted on the carriage for feeding sand to the projector, and means to permit lateral movement of the flask-support relatively to the projector to fill all portions of the flask.

7. In a molding machine, the combination of a rotatable carriage, a sand projector comprising a stator and a rotor mounted on the carriage, a flask support mounted on the carriage, means mounted on the carriage for feeding sand to the projector, and means to permit lateral movement of the flask-support relatively to the projector to fill all portions of the flask.

8. In a molding machine, the combination of a rotatable carriage, a sand projector comprising a stator and a rotor mounted on the carriage, a motor mounted on the carriage for driving the rotor, sand-conveying mechanism mounted on the carriage, and mechanism for rotating the carriage.

9. In a molding machine, the combination of a rotatable carriage, a sand projector comprising a stator and a rotor mounted on the carriage, a motor mounted on the carriage for driving the rotor, a flask-support mounted on the carriage, sand conveying mechanism mounted on the carriage, and mechanism for rotating the carriage.

10. In a molding machine, the combination of a rotatable carriage, a sand projector comprising a stator and a rotor mounted on the carriage, a motor mounted on the carriage for driving the rotor, a flask-support mounted on the carriage, sand-conveying

mechanism mounted on the carriage and driven by the motor, and mechanism for rotating the carriage operated by the motor.

11. In a molding machine, the combination of a rotatable carriage, a sand projector comprising a stator and a rotor mounted on the carriage, a motor mounted on the carriage for driving the rotor, a flask-support movably mounted on the carriage, sand conveying mechanism mounted on the carriage and driven by said motor, and mechanism driven by the motor for rotating the carriage.

12. In a molding machine, the combination of a carriage, a sand projector comprising a stator and a rotor mounted on the carriage, a flask-support mounted on the carriage, means mounted on the carriage for conveying and feeding sand to the projector, and a motor mounted on the carriage and connected to drive the rotor and the conveyer, said support being disposed so the excess sand in the flask may be discharged in front of the conveyer, for reconveying sand to the projector.

13. In a molding machine, the combination of a rotatable carriage, a sand projector comprising a stator and a rotor mounted on the carriage, a flask support mounted on the carriage, means mounted on the carriage for feeding and conveying sand to the projector, and a motor mounted on the carriage for driving the conveying means and rotor, said support being disposed so the excess sand may be discharged in front of the conveying mechanism for reconveying sand to the projector.

14. In a molding machine, the combination of a carriage, a sand projector comprising a stator and a rotor mounted on the carriage, a flask support mounted on the carriage, means mounted on the carriage for conveying and feeding sand to the projector, and means to movably sustain the flask support so as to permit lateral movement of the flask relatively to the projector, so that all portions of the flask may be filled.

15. In a molding machine, the combination of a rotatable carriage, a sand projector comprising a stator and a rotor mounted on the carriage, a flask-support mounted on the carriage, means mounted on the carriage for feeding and conveying sand to the projector, and means to movably sustain the flask support so as to permit lateral movement of the flask relatively to the projector, so that all portions of the flask may be filled.

16. In a molding machine, the combination of a carriage, a sand projector comprising a stator, and a rotor mounted on the carriage, a flask-support mounted on the carriage, means mounted on the carriage for feeding and conveying sand to the projector,

a motor mounted on the carriage and connected to drive the rotor and sand feeding means, and means to movably sustain the flask-support to permit lateral movement of the flask relatively to the projector, so that all portions of the flask may be filled.

17. In a molding machine, the combination of a carriage, a sand projector comprising a stator, and a rotor mounted on the carriage, a flask-support mounted on the carriage, means mounted on the carriage for feeding and conveying sand to the projector, a motor mounted on the carriage and connected to drive the rotor and sand feeding means, and means to movably sustain the flask-support to permit lateral movement of the flask relatively to the projector so that all portions of the flask may be filled and so the excess sand may be discharged in front of the conveying mechanism.

18. In a molding machine, the combination of a rotatable carriage, a sand projector comprising a stator and a rotor mounted on the carriage, a flask support mounted on the carriage, means mounted on the carriage for feeding sand to the projector, a motor mounted on the carriage and connected to rotate the carriage and drive said rotor, and means to movably sustain the flask-support so as to permit lateral movement of the flask relatively to the projector, so that all portions of the mold may be filled.

19. In a molding machine, the combination of a movable carriage, a sand projector comprising a stator and a rotor mounted on the carriage, a flask-support mounted on the carriage, a sand elevator and a sand conveyer supported on and movable with the carriage, mechanism mounted on the carriage for driving the elevator and conveyer and the projector, means mounted on the carriage for feeding sand to the projector, and means to permit relative lateral movement between the projector and the flask-support to fill all portions of the flask.

20. In a molding machine, the combination of a rotatable carriage, a sand projector comprising a stator and a rotor mounted on the carriage, a flask-support mounted on the carriage, a sand elevator and a sand conveyer supported on and movable with the carriage, mechanism mounted on the carriage for driving the elevator and conveyer and the projector, means mounted on the carriage for feeding sand to the projector, and means to permit relative lateral movement between the projector and the flask-support to fill all portions of the flask.

21. In a molding machine, the combination of a movable carriage, a sand projector comprising a stator and a rotor mounted on the carriage, a flask support mounted on the carriage, said carriage comprising a rigid arm on which the projector is supported,

means mounted on the carriage for feeding sand to the projector, and means to permit relative lateral movement between the projector and the flask support to fill all portions of the flask.

22. In a molding machine, the combination of a movable carriage, a sand projector comprising a stator and a rotor mounted on the carriage, a flask support, said carriage comprising an arm on which the flask-support is sustained, means mounted on the carriage for feeding sand to the projector, and means to permit relative lateral movement between the projector and the flask support to fill all portions of the flask.

23. In a molding machine, the combination of a movable carriage, a sand projector comprising a stator, and a rotor mounted on the carriage, a flask-support, said carriage comprising an arm rigid thereon, means mounted on the carriage for feeding sand to the projector, and supporting means for the support, permitting lateral movement of the flask support to fill all portions of the flask.

24. In a molding machine, the combination of a rotatable carriage, a sand projector comprising a stator, and a rotor mounted on the carriage, a flask support, said carriage comprising an arm rigid thereon, means mounted on the carriage for feeding sand to the projector, and supporting means for the support, permitting lateral movement of the flask-support to fill all portions of the flask.

25. In a molding machine, the combination of a carriage, a sand projector comprising a stator and a rotor mounted on the carriage, a flask support, said carriage comprising an arm rigid thereon, means mounted on the carriage for feeding sand to the projector and an adjustable supporting connection for the support connected to said arm.

26. In a molding machine, the combination of a movable carriage, a sand projector comprising a stator and a rotor mounted on the carriage, mechanism for driving the rotor mounted on the carriage, and means for delivering sand to the projector comprising an endless chain and buckets carried by the chain and at one side thereof.

27. In a molding machine, the combination of a movable carriage, a sand projector comprising a stator and a rotor mounted on the carriage, mechanism for driving the rotor mounted on the carriage, means for delivering sand to the projector comprising an endless chain and buckets carried by the chain and at one side thereof, and means mounted on the carriage for conveying sand to said buckets.

28. In a molding machine, the combination of a movable carriage, a sand projector comprising a rotor and a stator mounted on

the carriage, a flask support mounted on the carriage and means mounted on the carriage for delivering sand from the floor to the projector.

29. In a molding machine, the combination of a rotatable carriage, a sand projector comprising a rotor and a stator mounted on the carriage, a flask-support mounted on the carriage, and means mounted on the carriage for delivering sand from the floor to the projector.

30. In a molding machine, the combination of a movable carriage, a sand projector comprising a rotor and a stator mounted on the carriage, and means for delivering sand from the floor to the projector comprising a screw-conveyer and a curved wall in the back of said conveyer.

31. In a molding machine, the combination of a rotatable carriage, a sand projector comprising a rotor and a stator mounted on the carriage, mechanism for driving the rotor mounted on the carriage, a flask support mounted on the carriage, sand-conveying and elevating mechanism mounted on the carriage, and a pivotal support for the carriage.

32. In a molding machine, the combination of a rotatable carriage, a sand projector comprising a rotor and a stator mounted on the carriage, mechanism for driving the rotor mounted on the carriage, a flask support mounted on the carriage, sand-conveying and elevating mechanism mounted on the carriage, a pivotal support for the carriage, and means to vertically adjust the pivotal connection between the carriage and the support.

33. In a molding machine, the combination of a rotatable carriage, a sand projector comprising a rotor and a stator mounted on the carriage, mechanism for driving the rotor mounted on the carriage, sand conveying and elevating mechanism mounted on the carriage, a pivotal support for the carriage and an annular housing around said support.

34. In a molding machine, the combination of a carriage, a sand-projector comprising a rotor and a stator mounted on the carriage, mechanism for driving the rotor mounted on the carriage, a flask-support mounted on the carriage, sand conveying and elevating mechanism mounted on the carriage, a pivotal support for the carriage and an annular housing around said support.

35. In a molding machine, the combination of a movable carriage, a sand projector mounted on said carriage and comprising a stator and a rotor, a motor for driving the rotor mounted on the carriage, sand conveying mechanism mounted on the carriage, a toothed stationary track, a gear-wheel on

the carriage meshing with the toothed track, and mechanism driven from the motor for operating said gear to propel the carriage.

36. In a molding machine, the combination of a movable carriage, a sand projector mounted on said carriage, and comprising a stator and a rotor, a flask support on the carriage, mechanism for driving the rotor mounted on the carriage, sand conveying mechanism mounted on the carriage, a toothed stationary track, a gear-wheel on the carriage meshing with the toothed track, and mechanism driven from the motor for operating said gear to propel the carriage.

37. In a molding machine, the combination of a movable carriage, a sand projector mounted on said carriage and comprising a stator and a rotor, a motor for driving the rotor mounted on the carriage, a screw-conveyer mounted on the carriage and driven by said motor, a toothed stationary track, a gear-wheel on the carriage meshing with the toothed track, and mechanism driven from the conveyer for operating said gear to propel the carriage.

38. In a molding machine, the combination of a movable carriage, a sand projector mounted on said carriage and comprising a stator and a rotor, a motor for driving the rotor mounted on the carriage, a screw-conveyer driven from the motor on the carriage, and mechanism driven from the conveyer for propelling the carriage.

39. In a molding machine, the combination of a movable carriage, a sand-projector comprising a stator and a rotor mounted on said carriage, a motor for driving the rotor mounted on the carriage, sand conveying mechanism mounted on the carriage, a toothed stationary track, a gear-wheel on the carriage meshing with the toothed track,

mechanism driven by the motor for operating said gear to propel the carriage, and a cleaner for the track mounted on the carriage.

40. In a molding machine, the combination of a rotatable carriage, a sand projector comprising a stator and a rotor mounted on said carriage, a motor for driving the rotor mounted on the carriage, sand conveying mechanism mounted on the carriage, a toothed stationary circular track, a gear-wheel on the carriage meshing with the toothed track, and mechanism driven by the motor for operating said gear to propel the carriage.

41. In a molding machine, the combination of a rotatable carriage, a sand projector comprising a stator and a rotor mounted on said carriage, a motor for driving the rotor, mounted on the carriage, sand conveying mechanism mounted on the carriage, a toothed stationary circular track, a gear-wheel on the carriage meshing with the toothed track, mechanism driven by the motor for operating said gear to propel the carriage, and a cleaner for the track mounted on the carriage.

42. In a molding machine, the combination of a rotatable carriage, a sand projector comprising a stator and a rotor, mounted on said carriage, a motor for driving the rotor, mounted on the carriage, sand conveying mechanism driven by the motor and mounted on the carriage, and comprising a screw, a toothed stationary track, a gear-wheel on the carriage and meshing with the toothed track and reducing gearing between one end of the screw and said gear-wheel.

ELMER O. BEARDSLEY.
